RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed March 4, 1931, Serial No. 519,986. Renewed December 2, 1931.

My invention relates to railway traffic controlling apparatus, and particularly to automatic train control or cab signal systems of the continuous inductive type. More specifically my present invention relates to the trackway portion of such systems.

I will describe one form of trackway apparatus embodying my invention, and will then point out the novel features thereof in 10 claims.

The accompanying drawing is a diagrammatic view showing one form of trackway apparatus embodying my invention.

Referring to the drawing, the reference characters 1 and 1^a designate the track rails of a stretch of electric railway track along which traffic normally moves in the direction indicated by the arrow. These rails are divided by insulated joints 2, to form a plurality of track sections, of which only one section C—D is shown in the drawing, and the usual impedance bonds 18 are provided to conduct the propulsion current around the insulated joints.

Located adjacent the entrance end of section C—D, is a track relay E^c which, as here shown, is of the centrifugal type. This relay comprises a rotor 3, two stator windings 4 and 5, a centrifugal device 6 operated by the rotor 3, and a contact 7 which is closed when and only when the centrifugal device is rotating at or above a given speed. The stator winding 4 is connected across the track rails 1 and 1^a, and the other stator winding 5 is at times energized as hereinafter explained.

Located adjacent the exit end of the track section C—D is a track transformer F, the secondary 8 of which is connected across the track rails, and the primary 9 of which is at 49 times energized as hereinafter explained.

The track relay E^c controls a coding relay G in such manner that the coding relay is energized when and only when front contact 7 of relay E^c is closed. The circuit for the relay G is from terminal B of a suitable source of current, through contact 7 of relay E^c, and the winding of relay G to terminal O of the same source of current.

The coding relay G controls a coding device H, which device comprises an operating

winding 14, and two contacts 15 and 16 which are periodically closed at different rates when the winding 14 is energized. The circuit for winding 14 of the coding device H is from terminal X¹¹⁰, through back contact 12 of relay G, and the winding 14 to terminal Y. It follows that the coding device H is normally deenergized, but is set into operation when the coding relay G becomes deenergized.

When the coding relay G is energized, the primary 9 of transformer F and the stator winding 5 of relay E^c are both supplied with uninterrupted alternating current of normal voltage, such, for example, as 110 volts. The circuit for the transformer primary is from terminal X¹¹⁰ of a suitable source of alternating current, through the front point of contact 10 of relay G, and the primary 9 of transformer F to terminal Y of the same source. The relay winding 5 is connected in multiple 70 with the transformer winding 9 in this circuit.

Interposed between the transformer secondary 8 and the track rail 1^a, is the primary of an auxiliary transformer Z. The secondary of this transformer Z is connected with the input terminals of a full wave rectifier W, and the output terminals of this rectifier are connected with an auxiliary relay K through a back contact 13 of relay G. The relay K is so adjusted that it is normally open, and that when a train moving toward the right passes through section C—D, this relay will not close until the train reaches the exit end of the section.

When the section C—D is unoccupied, track relay E^c is energized by current of normal voltage in both of its windings, so that relay G is energized, and the parts are in the conditions in which they are shown in the drawing. When a train moving toward the right enters section C—D, it will deenergize relay E^c, thereby opening the circuit for the coding relay G at contact 7. The circuits previously traced for the primary 9 of transformer F and the winding 5 of relay E^c will then be opened at the front point of contact 10 of relay G, and a new circuit for these elements will be closed at the back point of the same contact. The circuit for transformer 100

primary 9 will then be from terminal X^{80} , through back contact 11 of relay G, back point of contact 20 of relay K, contact 15 or 16 of the coding device H, front or back point of contact 17 of relay E^D for the section in advance of section C—D, back point of contact 10 of relay G and transformer primary 9 to terminal Y. The relay winding 5 is connected in multiple with primary 9 as before. The voltage which is thus supplied to primary 9 and winding 5, is lower than normal, and may, for example, be 80 volts. The current thus supplied to these elements will be periodically interrupted at one rate or another by contact 15 or 16 of the coding device H, according as track relay E^D is energized or deenergized, that is, according as the section in advance of section C—D is unoccupied or occupied.

When the train approaches the exit end of section C—D, the current supplied to the auxiliary relay K will become sufficient to close this relay, thereby opening back point of contact 20 and closing the front point of this contact. This will open the circuits just traced for elements 9 and 5, and will close a new circuit for these elements, which circuit is from terminal X^{125} , through the front point of contact 20 of relay K, contact 15 or 16 of the coding device H, front or back point of contact 17 of relay E^D , and the back point of contact 10 of relay G to the elements 9 and 5. The current thus applied to the elements 9 and 5 will be at a higher voltage than before the operation of relay K, and the new voltage may, for example, be 125 volts. When the train passes out of section C—D, track relay E^C will become energized, and this will cause the coding relay G to become energized, thereby opening the circuit for the auxiliary relay K. The parts will then be restored to the conditions in which they are shown in the drawing.

In systems of the character described, it has been customary to supply uninterrupted alternating current at 110 volts to the primary 9 and track relay winding 5 when the section is unoccupied, and to supply periodically interrupted current at the same voltage to these elements when the section is occupied by a train. It has been found that under these conditions the train-carried apparatus which responds to the periodically interrupted or coded current in the track rails may be energized to an excessive value, and it has also been found that this over-energization reduces the sensitivity of the train-carried apparatus as far as concerns the detecting of a broken rail. That is to say, should one of the rails of section C—D be broken, the so-called "sneak" currents through the impedance bonds, the crossbonding between rails, and the unbroken rail, may be sufficient to falsely energize the apparatus on a train occupying this section. In accordance with my invention, the amount of current applied to

the track rails by the transformer F when the section is occupied, is reduced to such a value that it will satisfactorily operate the train-carried apparatus under normal conditions, but that in the event of a broken rail the sneak currents will not be of sufficient value to falsely energize the apparatus on the train, whereas when the train is about to leave the section, the voltage is again raised to such value that the track relay will immediately become effectively energized as soon as the section is vacated.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track, a centrifugal track relay for said section having two windings the first of which is connected across the rails at the entrance end of the section, a normally energized approach relay having a circuit controlled by a front contact of said track relay, a track transformer having its secondary connected across the rails at the exit end of said section through the primary of an auxiliary transformer, an auxiliary relay supplied with current from the secondary of said auxiliary transformer through a back contact of said approach relay and arranged to remain open when the section is occupied until the train approaches the exit end of the section, means operating when said approach relay is energized to supply uninterrupted alternating currents at normal voltage to the primary of said track transformer and to the second winding of said track relay, means operating when said approach relay is deenergized and said auxiliary relay is open to supply periodically interrupted alternating current at a voltage below normal to the primary of said track transformer and to the second winding of said track relay, and means operating when said approach relay is deenergized and said auxiliary relay is closed to again increase the voltage at which current is supplied to said track transformer primary and the second winding of the track relay.

2. In combination, a section of railway track, a centrifugal track relay for said section having two windings the first of which is connected across the rails at the entrance end of said section, means operating when said relay is energized to supply uninterrupted alternating current at normal voltage to the rails of the section and to the second winding of said relay, means operating when said track relay becomes deenergized due to the entrance of a train into said section to supply periodically interrupted alternating

current at reduced voltage to the rails and to said second relay winding, and means responding to the increased current drawn as the train approaches the exit end of the section for again increasing the voltage applied to the rails and to the second relay winding.

3. In combination, a section of railway track, a track relay having a winding connected across the rails at the entrance end of said section, a track transformer having its secondary connected across the rails at the exit end of said section through the primary of an auxiliary transformer, an auxiliary relay supplied with current from the secondary of said auxiliary transformer and arranged to remain open when the section is occupied until the train approaches the exit end of the section, means operating when said track relay is energized to supply uninterrupted alternating current at normal voltage to the primary of said track transformer, means operating when said track relay becomes deenergized due to the entrance of a train into said section to supply periodically interrupted alternating current to the primary of said track transformer, and means controlled by said auxiliary relay for varying the voltage at which periodically interrupted current is supplied to the primary of said track transformer.

4. In combination, a section of railway track, a track relay having a winding connected with the rails at the entrance end of said section, means operating when said relay is energized to supply current of one voltage to the rails of the section, means responsive to the deenergization of said relay to reduce the voltage of the current supplied to the rails of said section, and means operating when a train approaches the exit end of said section to again increase the voltage applied to the track rails.

5. In combination, a section of railway track, a track relay having a winding connected with the rails at the entrance end of said section, means operating when said relay is energized to supply uninterrupted alternating current at normal voltage to the rails at the exit end of said section, means responsive to the deenergization of said relay to supply periodically interrupted alternating current at a lower voltage to the rails at the exit end of said section, and means operating when a train approaches the exit end of said section to again increase the voltage applied to the rails.

6. In combination, a section of railway track, a track relay having a winding connected with the rails at the entrance end of said section, a track transformer having its secondary connected with the rails at the exit end of said section through the primary of an auxiliary transformer, a normally energized approach relay having a circuit controlled by a front contact of said track relay, an auxil-

iary relay supplied with current from the secondary of said auxiliary transformer to a back contact of said approach relay and arranged to remain open when the section is occupied by a train until the train approaches the exit end of the section, means operating when said approach relay is energized to supply uninterrupted alternating current at normal voltage to the primary of said track transformer, means operating when said approach relay is deenergized and said auxiliary relay is open to supply periodically interrupted alternating current at a lower voltage to the primary of said track transformer, and means operating when said approach relay is deenergized and said auxiliary relay is closed to again increase the voltage at which current is supplied to said track transformer.

7. A track circuit system including: a section of railway track, a normally closed track circuit including a relay and a source of current that is connected to the track as long as said relay holds a front contact closed, said relay being deenergized upon the entry of a train into the section, and means so controlled by the relay when deenergized and by the train that when the latter has advanced a distance within the limits of a section a source of current is connected to the track of such character as to energize, after the train has left the section, said relay to close its front contact.

8. A track circuit system including: a section of railway track, a normally closed track circuit including a relay and a source of current that is connected to the track as long as said relay holds a front contact closed, said relay being deenergized upon the entry of a train into the section, and means so controlled by the relay when deenergized and by the train that when the latter nears the end of the section, but before leaving it, a source of current is connected to the track of such character as to energize, after the train has left the section, said relay to close its front contact.

9. A track circuit system including: a section of railway track, a track relay, means controlled by the track relay to normally supply current to the track of a character sufficient to energize the track relay, means operating when the track relay becomes deenergized to supply to said track a train-control current of a character different from, and in place of, the current normally supplied to the track, and means, controlled by the train as it advances within the limits of the section, to supply to the track, while the train is still in the section, current of a character to energize the track relay after the train leaves the section.

10. A track circuit system including: a section of railway track, a track relay, means controlled by the track relay to normally sup-

ply current to the track of a voltage sufficient to energize the track relay, means operating when the track relay becomes deenergized to supply to said track a train control current of a lesser voltage in place of the current normally supplied to the track, and means, controlled by the train as it advances within the limits of the section, to supply to the track, while the train is still in the section, current of a voltage sufficiently high to energize the track relay after the train leaves the section.

11. A track circuit system including: a section of railway track, a track relay, means controlled by the track relay to normally supply current to the track of a character sufficient to energize the track relay, means operating when the track relay becomes deenergized to supply to said track a train control current of a character different from, and 20 in place of, the current normally supplied to the track, and means, controlled by the train as it advances within the limits of the section, to supply to the track, while the train is still in the section, a train control current of a 25 character to also energize the track relay after the train leaves the section.

12. A track circuit system including: a section of railway track, a track relay, means controlled by the track relay to normally supply current to the track of a voltage sufficient to energize the track relay, means operating when the track relay becomes deenergized to supply to said track a train control current of a lesser voltage in place of the current normally supplied to the track, and means, controlled by the train as it advances within the limits of the section, to supply to the track, while the train is still in the section, a train control current of a voltage sufficiently high 40 to energize the track relay after the train leaves the section.

In testimony whereof I affix my signature.
RONALD A. McCANN.
